Edward Hurd,
By his atty.,
J. S. Brown

United States Patent Office.

EDWARDS HURD, OF CHAMPAIGN COUNTY, OHIO.

Design No. 4,060, dated May 24, 1870.

DESIGN FOR AN AX.

The Schedule referred to in these Letters Patent and making part of the same.

To all whom it may concern:

Be it known that I, EDWARDS HURD, of the county of Champaign and State of Ohio, have invented a new and improved Design for a Chopping-Ax; and I do hereby declare that the following is a full and exact description thereof, reference being had to the accompanying drawing making part of this specification,

Figure 1 being a side view of the ax, and

Figure 2 an edge view of the same.

Like letters designate corresponding parts in both figures.

The ax is made of the length and proportions as represented, to concentrate the momentum, and cause it to sink deeper in the wood.

The head or poll B is made long or high, in proportion to the blade A, as shown, so that the head and blade balance, or nearly so, at the eye C, or on

the handle. By thus balancing the weight on the handle, the ax is easier to chop with, especially in felling trees, and its motion is guided with greater facility.

The blade A is so formed that the lines *a a a*, of equal thickness, shall form curves, as represented in fig. 1, thereby locating the line *b b* of greatest convexity in the direction and position shown. This form of blade is found to chip better than any other known to me.

I claim as my invention—

The design for an ax, substantially as herein shown and described.

EDWARDS HURD.
